UNITED STATES PATENT OFFICE.

ALFRED H. COWLES, OF SEWAREN, NEW JERSEY, ASSIGNOR TO THE ELECTRIC SMELTING AND ALUMINUM COMPANY, OF SEWAREN, NEW JERSEY.

PROCESS OF AND APPARATUS FOR FEEDING CARS INTO AND THROUGH TUNNEL-FURNACES.

1,073,219.

Specification of Letters Patent. Patented Sept. 16, 1913.

Original application filed March 16, 1911, Serial No. 614,876. Divided and this application filed May 12, 1911, Serial No. 626,856. Renewed February 12, 1913. Serial No. 748,016.

To all whom it may concern:

Be it known that I, ALFRED H. COWLES, a citizen of the United States, and a resident of Searen, in the county of Middlesex and State of New Jersey, have invented certain new and useful Improvements in the Process of and Apparatus for Feeding Cars Into and Through Tunnel-Furnaces, of which the following is a specification.

10 My invention relates to tunnel furnaces.

It relates further to tunnel furnaces of the Groendal type, such as are shown in Patent No. 876,712, of January 14, 1908.

15 This present application is a division of my application Ser. No. 614,876, filed Mar. 16, 1911.

It relates particularly to improved ways and means for feeding cars carrying briquets, or other material to be treated, into 20 and through furnaces.

It relates further to a method by which the speed of feeding the car through the furnace is controlled according to the heat desired in the furnace, thereby preventing 25 under or over heating and insuring economy.

The object of the invention is to provide a more economical, efficient and easily manipulated means for feeding the material gradually and uniformly into and through 30 such furnaces.

Hitherto the method of procedure has been to introduce a car carrying the material all at once, and causing a quick forward motion of the train of cars in the furnace, 35 to make room for the new load. This method is subject to various defects, among which may be mentioned jolts, by the cars being moved quickly of hitting against each other, and displacing some of the load.

40 Furthermore, a load when inserted bodily by one quick operation into the furnace, remains for a very considerable time exposed to the temperature of that portion of the furnace near the entrance, the other loads 45 under treatment remaining stationary and subject to the temperature ruling those portions of the furnace in which they stopped. This does not tend to the most uniform treatment of the loads, which is attained by

50 keeping the cars moving constantly and uniformly through the furnace, and bringing the loads successively into the varying zones of temperature.

To carry out my invention I have invented the device set forth in the drawings, 55 which illustrate one of the means by which my said invention may be practically applied.

In the drawings:—Figure 1 is an elevation of a Groendal tunnel, or channel furnace; Fig. 2, a longitudinal section through the portion at which the truck enters, showing details of the invention; Fig. 3, is a vertical section on the line $a-a$, of Fig. 2; Fig. 4 is a cross-section of the vestibule on the line $b-b$, of Fig. 2; Fig. 5 is an elevation, partly in section, of one form of my feeding mechanism, and Fig. 6 shows a section, on the line $x-x$, of Fig. 5, showing details of the truck-moving mechanism. 70

Referring to the drawings: 1 is the exterior of the furnace closed at one end by a vestibule 2 of my construction; 3 are rails for introducing into the vestibule 2 the transfer car 4 carrying rails 5, from which 75 the car 6 bearing the load 7 is run into the furnace.

6¹ are the cars already in the furnace into which they have been pushed over the track 5¹, of which the rails 5 form a continuation 80 when the loaded car is placed in the vestibule.

Projecting through the front wall 8 of the vestibule 2 is shown a means for pushing the truck 6 from the vestibule into the furnace. 9 is a rack to which a gradual uniform forward motion and a rapid return are imparted by the motor 10 acting on the rack through pulleys carrying the belt 11. Other equivalent means may be employed. 90 The larger pulley actuates the worm 12, the spur wheel 13, and the rack 9, through the pinion 14.

15, 15¹ is a reversing electric switch, between the points of which moves the contact lever 16, which is shifted at predetermined intervals by the pin 17 on the rack 9.

17¹ is a pin for shifting the switch lever 18 into the middle position on the outward run of the rack. 100

16¹ is a spring, showing one means of braking the outward movement of the rack.

18, 18¹ are the two vestibule side doors whose upper portion is shaped as a rack and adapted to be raised and lowered by the 105 motor 20, or by hand through the interme-

diation of the worm and gearing 19. These doors when down dip into sand seals 21, which I have arranged on the transfer car 4, and thereby seal practically air and gas 5 tight the doors 18, 18¹ of the vestibule 2.

22 is the door leading from the vestibule into the furnace, which is raised and lowered by means of the rack 22¹, worm 23, gear 24 and motor 25, or otherwise.

10 Attached to the transfer car in the sides at right angles to the axle 26 are angle irons 27 dipping into sand boxes or troughs 28, located on the floor of the vestibule. These sand seals, in combination with the seals 21, 15 located on the top of the transfer car, serve to seal the vestibule on all sides when the car is within the vestibule. The cars 6 and 6¹ are provided at their sides with downwardly projecting strips 29 which dip into 20 the sand channels 30, and seal the car 6¹ from the pit 31.

At any desired point or points I may introduce one or more thermostats, or pyrometers, as shown at b, Fig. 2. Here c, if a 25 thermostat is used, may be composed of two different metals having different degrees of expansion and contraction under change of temperature. This contact c stands either between the two points or on d or d¹, according 30 to the heat. The thermostat is connected by the conductors x y with the rheostat R, and throws into the motor circuit, or throws out, resistance, thereby controlling the current supplied to the motor, 35 and hence its speed.

The operation of my device is as follows:—Assume the furnace to be in full operation and ready to receive the loads under treatment. The door 18, or 18¹ (according 40 to the side from which the transfer car is to be introduced) is raised. The switch lever 16 in normal condition rests midway between the two contacts 15, 15¹, in the position shown by the dotted outline in Fig. 45 5. The current is turned on manually by placing the switch lever on the contacts 15. As soon as the transfer car, carrying the car 6 is introduced the doors 18, 18¹ are lowered into the sand seals 21. The door 50 22 is now raised, and current is sent into the motor, which immediately brings the inner end of rack bar 9 against the car 6 and continues to force it gradually and uniformly into the furnace. During this time, 55 the heat and gases from the furnace are retained within the vestibule by the sand seals 21 and 28. When the car 6 with its load has entirely entered the furnace, the pin 17 on the rack 9 comes into contact with 60 the lever switch 16 and throws it over onto the contacts 15¹ reversing the motor and returning the rack with a rapid motion to the original position. Braking the return movement may be effected, in one way, by 65 a spring 16¹ and the pin 17¹ meeting the

end of the lever 16 throws it off the contacts 15¹ into the central position, thereby shutting off the current from the motor. The inertia of the switch will retain it in the central position until it is again to be thrown into contact with 15. The furnace door 22 is now lowered, the side door 18 or 18¹ raised, and the transfer car run out over the rails 3 to receive another load.

Automatic regulation of the movement of the cars in the furnace is attained by making the movement of the cars dependent upon the heat desired in the furnace. A differential thermostat may be used for the purpose, such as is shown diagrammatically in Fig. 2. When the heat is normal, the contact c stands between the points d and d¹. Increase or decrease of heat causes c to make contact either with d or d¹, throwing in or out resistance and increasing or decreasing the speed of the motor 10.

In connection with the regulation of the rapidity of the car movement, in any given case, it is apparent that after the operation is once started, the rate of supplying heat from fuel should be approximately constant, and the required fuel is determined by a preliminary testing and arriving at the rate of fuel consumption for any given material under treatment. For instance if one is briqueting residues of pyrite roasters, a maximum temperature of about 2600 degrees is required, and in this case, a larger feed of oil or combustible gas would be required than would be the case were one backing hollow ware brick, that need only a maximum temperature of 1800 degrees F. It must be understood that this invention is to be used in conjunction with initiating or occasional adjustments of the fuel supply and drafts. By employing a pyrometer I can adjust my fuel and air feed until the maximum temperature in the hottest part of the furnace is that desired, and I may then set my thermostat at some point away and in a cooler part of the furnace, so that it stands at its neutral point. Then variation of the maximum temperature will operate the thermostat.

Having thus fully described and illustrated my invention, what I claim, is:—

1. A furnace of the channel type, comprising means for feeding cars carrying material to be treated into and through the furnace, in combination with mechanism actuated by variations in the furnace temperature and adapted to coördinate the speed of the feeding means to the rise and fall of the temperature of the furnace.

2. A furnace of the channel type, comprising a car feeding mechanism, an electric motor actuating said mechanism, a thermostatic device controlled by variations in the furnace temperature, an electric circuit connecting the thermostatic device with

the motor, and a rheostat in said electric circuit, adapted to be operated by the thermostatic device and coördinate the speed of the feeding mechanism with the desired 5 temperature of the furnace.

3. The process of feeding material to be treated resting on carriers through a furnace, which consists in differentially moving said carriers at variable speeds, said 10 variations in speed being controlled by the variations in the temperature of the furnace.

4. The process of feeding materials to be treated resting on carriers through a furnace, which consists in differentially moving said carriers at variable speeds, said 15 variations of speeds being controlled by the variations of temperature of the furnace, and under conditions of fixed consumption

of fuel to which the material shall be 20 treated.

5. The process of feeding material to be treated resting on carriers through a furnace, which consists in differentially moving said carriers at variable speeds, said 25 variations of speed being controlled by the variations of the temperature of the furnace, so as to effect a desired maximum temperature constant within the limits of regulation.

Signed at Sewaren in the county of Middlesex and State of New Jersey this sixth day of May A. D. 1911.

ALFRED H. COWLES.
